GLASS RUN GUIDE CHANNEL

Alfred H. Haberstump, Detroit, Mich., assignor to
 The Murray Corporation of America, Detroit,
 Mich., a corporation of Delaware

Application July 29, 1938, Serial No. 222,012

2 Claims. (Cl. 296—44.5)

The present invention relates to structures for movably connecting a window or the like to a supporting structure therefor, and in particular provides an improved glass run guide channel 5 assembly for a vehicle window.

The principal objects of the present invention are to provide a construction of the above generally indicated character, wherein the connection between the window and its supporting structure is constituted by one or more rollers carried by one of the members and a rail carried by the other members; to provide such a structure wherein the rollers are of either inwardly or outwardly presenting V-form, and the rails are 10 complementarily formed, so that the rollers and the rails cooperate to support the glass against movement parallel to the plane of the glass and also against movement transversely of the plane of the glass; to provide such a structure wherein 15 one or both of the rail members is resiliently supported, so that the rollers are at all times resiliently urged into engagement with the rails provided therefor; and to provide such a structure which may be economically manufactured, 20 assembled and installed and which is quiet and reliable in operation.

With the above as well as other more detailed objects in view, which appear in the following description and in the appended claims, preferred but illustrative embodiments of the invention are shown in the accompanying drawings throughout the several views of which corresponding reference characters are used to designate corresponding parts and in which:

Figure 1 is a fragmentary view, with certain of the parts broken away, of a vehicle door construction embodying the invention;

Fig. 2 is a detail view, taken along the line 2—2 of Fig. 1;

Fig. 3 is a detail view, taken along the line 3—3 of Fig. 1;

Fig. 4 is a detail view, taken along the line 4—4 of Fig. 3;

Fig. 5 is a detail view, taken along the line 5—5 of Fig. 1;

Fig. 6 is a detail view, taken along the line 6—6 of Fig. 1;

Fig. 7 is a detail view, taken along the line 7—7 of Fig. 1; and

Figs. 8 and 9 are views of a modified embodiment of the invention.

It will be appreciated from a complete understanding of the present invention, that, in a generic sense, the improvements thereof may be embodied in widely different forms, intended for

widely different applications. In its preferred forms, however, the invention is particularly well adapted for use in conjunction with the doors of automotive vehicles and, in an illustrative but not in a limiting sense, the improvements are so disclosed herein. 5

Referring first to the embodiment of the invention shown in Figs. 1 through 7, the improved door comprises generally a window or glass 10, and a lower body portion designated as a whole 10 as 12. The body portion 12 is conventionally formed to have spaced inner and outer panels 14 and 16 respectively, which are joined together along their marginal edges by a rail 18 which, as will be understood, extends throughout the 15 front, bottom, and rear edges of the door. The glass 10, which is provided with the usual molding 20, is movable from the elevated position shown in Fig. 1 to a lower position in which it is entirely concealed within the body of the door. 20 The window movement is controlled in accordance with conventional practice by the window regulating mechanism designated as a whole 22.

The present invention is concerned primarily 25 with the structure employed in guiding the window 10 in its up and down movements relative to the door body 12, and in this instance, the door body 12 is provided with vertically extending grooved rails 25 and 26, which are engaged respectively by rollers 28 supported adjacent one edge of the window 10 and rollers 30 which are supported on the window 10 adjacent the other edge thereof.

The rollers 28, the peripheral surfaces of which 35 are formed of generally V-shape, complementary to the grooved form of the associated rail 24, are rotatably supported in a channel-shaped bracket 32, which extends downwardly from the corresponding corner of the window in continuation of the molding 20. To give additional support to the bracket 32, a supporting plate 36 is secured to one edge thereof, and extends inwardly of the door therefrom. The plate 36 is connected to an angularly extending bracket 38, the 40 other end whereof is secured as by welding to the lower marginal edge 20a of the window molding. The rollers 28 are rotatably journaled within the bracket 32 by means of pins 40 (Fig. 3), and the base 42 of the bracket 32 is provided with 45 spaced apertures, through which the peripheries of the rollers 28 project. The rollers 30 are correspondingly supported in downwardly depending relation from the other corner of the window 10, by means of a bracket 44. 50

The rail 26 associated with the rollers 30 is secured in fixed position relative to the corresponding edge of the door 12, by means of upper and lower channel-shaped brackets 46 and 48 (Figs. 5 and 2 respectively), the legs whereof embrace the legs of the rail 26 and are suitably secured thereto as by welding. The bracket 46 is secured to the rail 18 of the door by a stud 50 which passes through an opening in the rail, and is threaded 10 into a lug 52 which is fitted in the base of the bracket 46. The bracket 48 is correspondingly secured to the rail 18 by means of a stud 54.

Provision of the groove-like bearing relation between the rollers and the rails is regarded as being a feature of substantial importance in the practice of the present invention. It will be understood that this groove-like bearing relation enables the rollers and the rails to give guiding support to the window against sidewise movement 20 of the window in a direction parallel to the plane of the window, and to also give guiding support to the window against movement transversely to such plane. The single series of rollers and rails, accordingly, give complete guiding support to the window and at the same time does not interfere with the free rolling movement thereof.

A feature of the present invention resides in arranging the supporting and guiding structure for the window 10 in such a way that such supporting and guiding structure resiliently embraces the window, so as to permit free rolling movement thereof relative to the rails, and to also avoid rattling of parts and take up wear between the rollers and the rails. In the illustrated instance, this feature is provided by mounting the rail 26 for limited yielding movement in the plane of the window. As illustrated, the rail 24 is supported adjacent the corresponding rail of the door by means of a lower bracket 60 and an upper bracket 62. The brackets 60 and 62 (Figs. 7 and 3) are each of generally channel-shape, the legs whereof embrace the legs of the rails 24. The bracket 62 is provided with a leaf or other spring element 64, the back whereof bears against the rail 24 and urges the same to the right as viewed in Fig. 3. The spring 64 thus acts to yieldingly hold the rail 24 in engaging relation to the rollers 28, and at the same time, provides a definite limit to inward movement of the rail 24 relative to the bracket 62. A corresponding limit to outward movement of the rail 24 is afforded by inwardly flanging the marginal edges 66 of the bracket 62, so that they lie in blocking relation to the legs of the rail 24. The spring 64 is preferably retained in the bracket 62 by providing the latter with inwardly directed tongues 68 adjacent the end thereof, which are received in corresponding notches 70 formed in the end of the spring 64. It will be understood that the free length of the spring 64 is in excess of the spacing between the tongues 68, so that a bow is introduced into the spring when it is snapped into place between the tongues 68. It will be understood by reference to Fig. 7, that the rail 24 is correspondingly secured within the lower bracket 60, and that the spring 72 thereof correspondingly bears against the outer surface of the rail 24. With this relation, both ends of the rail 24 are continuously acted upon by the springs 64 and 72 and so resiliently but yieldingly embraces the rollers 28 in all positions of the window 10 relative to the door body 12.

In the illustrated instance, in order to limit vertical movement of the rail 24 relative to the brackets 60 and 62, the rail 24 is provided adjacent its upper and lower ends with outwardly

struck tongues 74 and 76 which pass through corresponding slots such as 78 (Fig. 7) formed in the corresponding leg of the associated bracket. The slots such as 78 are elongated in the direction of yielding movement of the rail 24, and so do not interfere with the aforementioned yielding movement of the rail. At the same time, these slots form an effective connection preventing vertical displacement of the rail 24 from the brackets 60 and 62. 10

The upper bracket 62 is secured to the inner panel of the door 14 by means of a bracket 80, the outwardly turned legs 82 whereof are welded or otherwise secured to the corresponding leg of the bracket 62, and the base whereof is secured 15 to the panel 14 by means of studs 84.

The lower bracket 60 is rigidly but adjustably secured to the rail 18 of the door 12 by means of a connection constituted by two angle brackets 86 and 88, which are connected respectively to the bracket 60 and the rail 18, and which are connected together in adjustable relation by means of a stud 90.

In certain instances, it is desirable to reinforce the roller-supporting brackets such as 32 and 44, 25 so as to maintain a predetermined spacing between the side walls thereof and overcome any otherwise existing possibility of such legs being inwardly deformed so as to bind upon the associated rollers such as 28 and 30. In such instances, it is preferred to provide the arrangement shown in Fig. 6, wherein the bracket 44 is provided with a channel-shaped filler plate 100, which is retained within the bracket by means of a stud 102, the threaded end whereof is threaded into 35 a plug 104 which is inserted through an associated opening provided in the base of the bracket 44.

Fig. 6 further illustrates an additional feature which is frequently utilized in the practice of the 40 invention. In the arrangement shown specifically in Figs. 1, 2, 3, 4, 5 and 7, the molding 20 for the window is constituted by a sheet of stock bent into generally channel form, the ends whereof are extended downwardly to constitute the previously 45 described bracket portions 32 and 44. In certain instances, it is desirable, in the interest of economy, to constitute the molding by a backing portion of relatively heavy section and a surface portion of relatively light section. This relation is 50 shown particularly in Fig. 6, in which the backing portion is represented by the reference character 44 and the relatively light surface wherefor is represented by the reference character 106.

In the modified embodiment of the invention 55 shown in Figs. 8 and 9, the rail 110, associated with one edge of the window, is rigidly secured to the inner panel 112 of the door 12, by means of brackets, one whereof is designated 114 and is held in place by a stud 116. The companion rail 118 is yieldably secured to the rail of the door adjacent the opposite edge of the window by means of upper and lower brackets 120 and 122, which correspond generally to the previously described brackets 60 and 62. The brackets 120 and 122 60 are of generally U-shaped form, and the rail 118 is slidably received between the legs thereof. The inner marginal edges such as 124 of the brackets 120 and 122 are inwardly turned to limit movement of the rail 118 inwardly of the door, and the base of the rail 118 is engaged by compression springs 126 and 128. The legs of the brackets 120 and 122 are inwardly depressed as is indicated at 130 and 132, to define a reduced area, so as to give guiding support against lateral movement of 70 75

the spring 128 relative to the rails. The brackets 120 and 122 are also supported upon the door rail 18' by means of channel-shaped brackets 134, the legs whereof extend generally perpendicular 5 to the nicked-in portions 130 and 132, and cooperate with such nicked-in portions to define completely enclosed wells or recesses to receive the springs 128.

In addition to the distinctions discussed above, 10 it is also preferred to the embodiments of Figs. 8 and 9, to utilize rollers 140 of grooved form, and to form the associated rails 110 and 116 with inverted V-shaped portions adapted to enter the grooves in the peripheries of the rollers. In all 15 other respects, the arrangement of Figs. 8 and 9 may and preferably does follow the construction described above in detail with reference to Figs. 1 to 7.

From the foregoing, it will be appreciated that 20 in each of the described embodiments, the window is guided in its upward and downward movements relative to the door by means of a rolling connection between the window and the supporting channel guide. Moreover, the relation is one 25 wherein the rollers and the cooperating guide rail portions cooperate together to limit sidewise movement of the glass in the plane thereof, and to also limit movement of the glass transversely to the plane thereof. In addition, the guiding connection is such that a resilient support for 30 the window is provided by the guiding structure. The resultant window-supporting structure is extremely simple of manufacture and assembly, and

is also found in practice to be quiet and reliable in operation.

It is to be understood that various modifications in the form, number and arrangement of parts may be made without departing from the spirit 5 and scope of the invention.

What is claimed is:

1. The combination in a door having a well, of a window glass in said well, a frame around said glass which is extended at opposite edges to form 10 legs therebelow, a pair of spaced rollers journalled on each said leg, said rollers having truncated conical side faces, channel shaped rails within the well of said door, the webs of which are extended to form channels having converging sides with 15 which the faces of said rollers engage, and spring means relatively urging said rails toward each other.

2. The combination in a door having a well, of a window glass in said well, an inverted U-shaped 20 frame of inwardly presented channel section engaging the top and side of said glass and projecting therebelow, an additional element engaging the bottom edge of the glass and joined to said frame above the projecting portions thereof, rollers in the channel of said projections extending through the web thereof, the side face of said rollers being of truncated conical shape, channel shaped rails having a V-shaped channel in the web thereof engaged by said rollers, and spring 25 30 means for relatively urging said rails toward each other.

ALFRED H. HABERSTUMP.
